UNITED STATES PATENT OFFICE

2,548,176

AMPLIFIER

Paul T. Semm, Batavia, and Robert T. Nakasone,
Chicago, Ill., assignors to Wheeleo Instruments
Company, Chicago, Ill., a corporation of Illinois

Application November 30, 1948, Serial No. 62,746

2 Claims. (Cl. 323—75)

1

Our invention relates to an improved amplifier for slowly varying currents or signals.

It is frequently desirable to amplify slowly varying currents or signals, such as the signals achieved from a photoelectric cell exposed to light of slowly varying intensity. Mechanisms for this purpose have heretofore been difficult and expensive in construction since they have either involved D.-C. amplifiers with the attendant requirements of critically stable tube characteristics and applied voltages, or chopping devices to convert the D.-C. signal to an alternating wave.

In accordance with the present invention, the foregoing problems are overcome and improved operation is secured by providing a saturable reactor energized by the slowly varying current. This reactor is connected in a bridge circuit energized by alternating current. The resultant voltage is rectified and fed back to the reactor.

It is therefore a general object of the present invention to provide an improved amplifier suitable for use in amplifying current changing slowly with time.

Another object of the present invention is to provide an improved amplifier for use with a photo-cell.

Still another object of the present invention is to provide an improved sensitive amplifier for slowly varying signals that requires no chopper or like device and does not demand tubes having particularly stable characteristics or voltage supplies having a high degree of stability.

The novel features which we believe to be characteristic of our invention are set forth with particularity in the appended claims. My invention itself, both as to its organization and method of operation, can best be understood by reference to the following description taken in connection with the accompanying drawing, in which the single figure shows an illustrative embodiment of the invention.

Referring now to the drawing there is shown generally at 10 a saturable reactor having saturating leg 10a and saturable legs 10b and 10c. Saturating windings 12 and 14 are received on leg 10a and saturable winding 16 has two like portions one on leg 10b and the other on leg 10c.

The winding 12 receives a signal or time-varying current by reason of the series circuit de-

2

fined by unidirectional voltage source 18, photo-cell 20 and winding 12. Thus the saturating leg 10a carries the current or signal to be amplified.

The photo-cell 20 may be any one of various types such as, for example, a gas, vacuum or multiplier tube or a lead sulfide cell. It is exposed to illumination of intensity varying slowly with time, thus causing current flow through winding 12 varying in like manner with time.

If desired, a photo-voltaic cell may be used to energize winding 12. In this case no battery 18 is required.

The winding 16 is in circuit relationship with inductor 22 and resistances 24 and 26 to define a bridge circuit having one set of opposed terminals 28 and 30 and another set of opposed terminals 32 and 34.

Alternating voltage is applied across the opposed bridge terminals 32 and 34 by the transformer 36 which is energized by alternating voltage source 38.

Output voltage from the bridge is taken across terminals 28 and 30. For this purpose the primary winding 38a of transformer 38 is connected directly across these terminals. This transformer has two secondary windings, 38b and 38c, the former acting as an output winding and the latter as a feedback winding.

The feedback winding 38c is connected to the input set of opposed terminals 40a and 40b of bridge rectifier 40. The output set of opposed terminals 40c and 40d is connected through variable resistance 42 to the saturating winding 14. Thus the winding 14 is energized in response to the voltage induced in winding 38c.

The rectifier 40 and winding 14 are poled to cause winding 14 to act as a negative feedback winding to oppose the action of winding 12. That is, when current flow through winding 12 increases, the unbalance of the bridge and the resultant change in output voltage of rectifier 40, causes current flow through winding 14 in direction to oppose the magnetomotive force or saturating effect of winding 12 giving rise to that current.

Preferably the bridge constants are chosen to achieve balance when no current flows in winding 12.

If desired, the winding 14 may be poled to aid rather than oppose winding 12. In this case the

sensitivity of the amplifier is increased but the stability and speed of response are reduced.

The output winding 38b is connected to the voltage dividing resistors 44, 46, and 48, the latter resistance comprising a switch 48a selectively connectable to resistances 48b, 48c or 48d. The common connection of resistors 48 and 46 is connected to the control electrode of electron tube 50. The opposite end of resistor 48 is connected to the cathode of tube 50 through resistors 52 and 54.

Adjustment of resistance 48 varies the scale range of the instrument 60.

Unidirectional cathode-anode space path voltage is applied to the electron tube 50 by unidirectional voltage source 56 and resistance 58 which are in series circuit relation across this path.

Meter 60 is an alternating current ammeter responsive to the effective value of the alternating current and is connected in series with the capacitor 62 and resistance 64 between the anode of tube 50 and the resistance 52.

Condenser 62 blocks D.-C. current flow through meter 60.

It will be observed that source 56 is connected to the junction of resistors 52 and 54. This provides stabilizing negative feedback for amplifier tube 50 and thus causes the deflection of meter 60 to correspond more exactly with the value of the induced voltage in winding 38b.

The saturable reactor 10 defines an inductance of value determined by the net magnetomotive force exerted on leg 10a by the windings 12 and 14. When this magnetomotive force increases, the legs 10b and 10c saturate and inductance of coil 16 is reduced. Current flow in coil 16 does not influence windings 12 and 14 because the flux associated with this coil is confined to legs 10b and 10c and the connecting portions of the core 10.

It will be observed that in the mechanism of the present invention we have provided a simple and reliable device capable of amplifying the very low power level and very slow current changes in photo-cell 20 to produce a usable indication on meter 60. This is accomplished in a highly stable and sensitive manner and, moreover, does not require either a D.-C. amplifier or a chopper.

While we have shown the amplifier of the present invention adapted to actuate meter 60, it will be evident that it may be used for other purposes as well. It may, for example, actuate a resetting mechanism operable to rebalance the bridge or form part of a closed cycle control system operable to maintain a constant illumination on the photoelectric cell 20. These, and many other uses will be apparent to one skilled in the art.

While we have shown a specific embodiment of our invention it will, of course, be understood

that we do not wish to be limited thereto since many modifications and alternative constructions may be made without departing from the spirit and scope thereof. We therefore claim by the appended claims to cover all such modifications and alternative constructions as fall within the true spirit and scope of our invention.

What we claim as new and desire to secure by Letters Patent of the United States is:

1. An amplifier adapted to respond to a slowly varying current from a low energy level source without reacting thereon comprising in combination, a saturable reactor having a saturating leg and a saturable leg, a winding on the saturating leg adapted to carry said current, a winding on the saturable leg, means defining a bridge circuit incorporating said last winding, means to apply alternating potential across one set of opposed terminals of said bridge circuit, an output transformer having a primary winding and a secondary winding, means connecting the primary winding across the other set of opposed terminals of the bridge circuit, a rectifier connected across the secondary winding, a second winding on the saturating leg of the saturable reactor, and means connecting the output terminals of the rectifier to said last winding.
2. An amplifier adapted to respond to a slowly varying current from a low energy level source without reacting thereon comprising in combination, a saturable reactor having a saturating leg and a saturable leg, a winding on the saturating leg adapted to carry said current, a winding on the saturable leg, means defining a bridge circuit incorporating said last winding, means to apply alternating potential across one set of opposed terminals of the bridge circuit, an output transformer having a primary winding and a pair of secondary windings, means connecting the primary winding across the other set of opposed terminals of the bridge circuit, a rectifier connected across one secondary winding, a second winding on the saturating leg of the saturable reactor, means connecting the output terminals of the last winding to the rectifier, and means responsive to the alternating E. M. F. in the other secondary winding to indicate the value of said current.

PAUL T. SEMM.
